LINE-STOP FOR TYPOGRAPHICAL MACHINES.

1,392,792.

Specification of Letters Patent.

Patented Oct. 4, 1921.

Application filed November 27, 1920. Serial No. 426,825.

To all whom it may concern:

Be it known that I, EDWIN WALTER PIERSON, a citizen of the United States, residing at Newark, in the county of Essex and State 5 of New Jersey, have invented new and useful Improvements in Line-Stops for Typographical Machines, of which the following is a specification.

The present invention relates to improvements in typographical machines and more especially to those of the linotype class which employ a so-called "first elevator," the function of which is to receive an assembled line of matrices and spacers from a line 10 delivery carriage, lower the line so received to the casting mechanism and to subsequently elevate the line to a higher level for transfer to a so-called "second elevator" for delivery to the matrix distributor.

20 In the practical operation of typographical machines of this type, it has been found that the end matrices in the line contained in the first elevator are liable to become separated from the remaining matrices in the 25 line and to become turned or otherwise displaced, thus causing jamming of the line during transfer thereof from the first elevator, and in some cases, the end matrices drop from the elevator. This displacement or 30 dropping of the end matrices of the line is likely to occur particularly during the ascent of the first elevator following a casting operation, it being caused by jarring or vibration incident to the operation of the machine, 35 and it is very apt to occur when the assembled line in the first elevator is used repeatedly to produce duplicate type slugs, in which case, the same line of matrices and spacers remains in the first elevator and is 40 elevated to the transfer position and lowered to the casting position incidental to the casing of each type slug.

The object of the present invention is to 45 provide a novel and improved line stop in the first elevator which is capable of accommodating itself automatically to the length 50 of each line received by the first elevator, thus compensating for any variation that may occur in the length of the lines, without 55 requiring manual setting or adjustment by the operator, and which will function to properly position and prevent displacement or dropping of the matrix at the forward or advanced end of the line, these results being attained in such manner that the line

stop will have a minimum movement incidental to the reception of each line by the first elevator, in consequence of which, wear is reduced to a minimum and efficiency of operation is attained.

To these and other ends, the invention consists in certain improvements and combinations and arrangements of parts, all as will be hereinafter more fully described, the features of novelty being pointed out particularly in the claims at the end of the specification.

In the drawings:—

Figure 1 is a perspective view of a portion of the first elevator and the line delivery 70 carriage of a typographical machine of the linotype class, the same having the present invention embodied therein;

Fig. 2 is a front elevation of the upper end of the first elevator, the front jaw thereof 75 being broken away, and a part of the cooperative line delivery carriage, as shown in Fig. 1; and

Fig. 3 represents a transverse section on the line 3—3 of Fig. 2.

Similar parts are designated by the same reference characters in the several views.

The present invention is applicable generally to typographical machines of the linotype class employing a first elevator which 85 receives a line of matrices and spacers from a line delivery carriage, lowers the same to the casting mechanism and subsequently elevates the line for delivery to distributing mechanism, and the invention is also applicable generally to typographical machines 90 having an element equivalent to the so-called first elevator used in machines of the linotype class. The preferred embodiment of the invention is herein shown and will be 95 described in detail. It is to be understood, however, that the invention is not restricted to the precise construction shown, as equivalent constructions are contemplated and these will be included within the scope of the 100 claims.

In the present instance, 1 and 2 represent the front and rear jaws respectively of a first elevator of the kind generally used in typographical machines of the well known 105 linotype class, these jaws being secured together in fixed relation, at the lefthand end of the elevator by an interposed block 3. The opposite or righthand end of the elevator is open to receive the line of matrices, 110

and the inner faces of the jaws 1 and 2 are grooved to provide channels 5 and 6 to receive the ears on the upper ends of the matrices and to thus support and guide the 5 matrices. The matrices M are preferably of the standard kind and the spacers S are also preferably of the standard wedge or expansible type. It will be understood that the first elevator is positioned at one level 10 to receive the composed line of matrices and spacers, the line entering the elevator from the right (Figs. 1 and 2), after which the elevator descends until the rear jaw 2 is immediately above the mouth-piece of the 15 metal pot, after which the metal pot is caused to move forward, bringing the mouth-piece thereof into contact through the mold with the character-bearing portions of the matrices in the line, and after 20 the cast has been made and the metal pot retracted, the first elevator rises, it passing above the level at which it received the line of matrices and reaching a point where the line is transferred from the first elevator for 25 delivery to distributing mechanism. The line delivery carriage which introduces the composed line of matrices and spacers into the first elevator may be of the construction generally employed for this purpose, the 30 line delivery carriage shown comprising a pair of fingers 7 and 8 which are adapted to receive the composed line endwise between them, after which the fingers are shiftable in unison, thus carrying the line endwise into the first elevator. The finger 7 which is located at the rear or righthand end of the line, is carried by a slide which is composed of slide blocks 9, 10 and 11 which are adapted to reciprocate in a 35 grooved guide which extends from the assembling elevator to the first elevator, these slide blocks being connected by rails 12, and the finger 8 is carried by slide blocks 13 and 14 which are connected by a rail 15 which is slidable relatively to the rails 12, this arrangement causing the fingers 7 and 40 8 to move in unison during the operation of the line delivery carriage, but permitting relative adjustment of the fingers to 45 vary the distance between them in order that 50 they may be set to accommodate lines of different lengths.

It will be understood that during the operation of transferring a composed line of 55 matrices and spacers from the assembling elevator to the first elevator, the line of matrices and spacers is carried into the first elevator by the fingers 7 and 8 which engage the opposite ends of the line, these fingers 60 projecting downwardly through the space formed between the front and rear jaws 1 and 2 of the first elevator. Suitable devices are now in use for confining and preventing displacement of the righthand or 65 rear end of the line after the same has been

introduced into the first elevator. The present invention provides a novel and improved device for confining and preventing displacement of the matrix at the lefthand or forward end of the line, after the line 70 has been introduced into the first elevator. This device is in the form of a line stop 75 which comprises preferably a pair of slide bars 16 which are connected together at one end, as at 17, and these slide bars, which extend in parallelism, are shaped and spaced to fit and slide longitudinally in the matrix supporting channels 5 and 6 of the first elevator. These slide bars extend into the first elevator from the lefthand side 80 thereof and their righthand ends form abutments in the matrix channels against which the upper matrix supporting lugs of the foremost matrix in the line abut when the line is introduced into the first elevator. 85 The slide bars are spaced apart sufficiently to straddle the finger 8 of the line delivery carriage. A tension spring 18 which may be connected at one end to the cross piece 17 and at its opposite end to the spacing 90 block 3, acts to urge the line stop comprising the slide bar 16 toward the right (Figs. 1 and 2), or toward the matrix receiving end of the first elevator. Means is provided for restraining movement of the line stop under 95 the influence of the spring 18, at certain times. Preferably and as shown, this restraining device comprises a friction plunger 19 which is guided to operate vertically in the top of the first elevator and is provided with a spring 20 which always acts to force the plunger downwardly and to produce a frictional engagement between its lower end and the top edge of one of the slide bars 16 of the line stop, the frictional 100 resistance thus offered being sufficient, when the plunger 19 is unrestrained, to prevent movement of the line stop under the influence of its spring 18. Means is also provided for retracting the friction plunger 105 and thus permit the line stop to shift longitudinally in the matrix channels so that the line stop may accommodate itself to the length of the line received by the first elevator. Preferably, and as shown, the restraining 110 or releasing device for the friction plunger comprises a shaft 21 which is pivoted on the top of the first elevator and is provided with an arm 22 arranged to engage beneath a head 23 on the projecting upper end of the 115 friction plunger and a second arm 24 which is also fixed to the shaft 21 and is arranged to be engaged and depressed by a pin or projection 25 carried by the line transfer carriage, the pin or projection 25 assuming a 120 position which will cause it to depress the arm 24, and hence to lift or retract the friction plunger 19 when the line delivery carriage reaches the limit of its lefthand or 125 line delivery movement. 130

The mode of operation of the line stop is as follows: The line of matrices and spacers which have been received between the fingers 7 and 8 of the line delivery carriage, from the assembling elevator, as is well understood, is shifted endwise by the line delivery movement of the carriage, the composed line being thereby introduced into the first elevator. This movement of the line delivery carriage, which movement is fixed or definite, will bring the foremost or lefthand end matrix in the line into a position in the first elevator, which will be determined by the length of the composed line.

10 As the line delivery carriage approaches the limit of its line delivery movement, the pin 25 thereon engages and depresses the arm 24, thereby retracting the friction plunger 19. The line stop is thereby released and 15 if the line received by the first elevator is longer than the immediately preceding line, the foremost or lefthand end matrix of the line will engage the righthand ends of the slide bars 16 of the line stop and will push 20 the latter toward the left until the composed line has been fully introduced into the first elevator. On the other hand, should the line received be shorter than the immediately preceding line, the line stop upon 25 being released by the final portion of the line delivery movement of the carriage, will advance or shift toward the right, under the influence of its spring 18, until the right-hand ends of the slide bars 16 abut against 30 the foremost or lefthand end matrix in the line. If the line received by the first elevator is of the same length as the preceding line received by it, the line stop will be released when the line delivery carriage sub- 35 substantially reaches the limit of its line delivery movement, but the movement of the line stop will be very small or insignificant. In any case, the line stop will adjust itself automatically to the length of each line received by the first elevator. Immediately 40 following the reception of the line of matrices from the line delivery carriage, the first elevator descends to present the composed line to the casting mechanism, in a manner that is well known in the art, and the initial part of this descent carries the arm 24 downwardly out of contact with the tripping pin 25 on the line delivery carriage, in consequence of which the spring plunger 45 19 will immediately reengage the line stop and thus restrain it from movement in either direction, and the line stop will then confine the lefthand end matrix and prevent its displacement. The line stop remains in 50 this condition during the subsequent ascent of the first elevator which carries the line up past the level at which the line was received, to a position where the line is transferred from the first elevator to the so-called second elevator, from which the mat-

rices are conveyed to the distributor, as is well understood by those familiar with the art, and the line stop is not released until the next succeeding line of matrices and spacers is delivered to the first elevator, 70 whereupon it is released and it accommodates itself to the length of the line, as before.

It has been customary heretofore to employ a line stop which was held in set position by a set screw or clamp, the line stop being reset manually each time the line measure was changed. With the advent of modern improvements in typographical machines of this class, it has become desirable 75 or necessary to make these changes in line measure frequently, and the consequent necessity of manually changing the setting of the line stop to correspond with the changes in line measure of the machine has 80 proven to be very inconvenient and it has caused the loss of much time. Also the patent granted to H. A. Armstrong, No. 1,108,825, granted August 25, 1914, shows and describes an automatic or self-adjusting 85 line stop, but in that case the line stop returned to the righthand or entrance end of the elevator each time a line was transferred from the elevator and each incoming line would push the line stop to the left for a 90 distance equal substantially to the extent of movement of the line in entering the elevator, the line stop being held in the position to which it was thus advanced by friction. While that arrangement accommodated it- 95 100 self automatically to the length of the line, it has the disadvantage that it requires the line stop to be moved the full length of the line with each delivery of a new line to the elevator, this wide range of movement of the line stop tending to cause excessive wear, especially as the line stop was held in place by friction which precluded entirely free movement of the line stop. The present invention provides a line stop which possesses 105 substantial advantages over those referred to. It is entirely automatic in its operation, thus avoiding inconvenience and loss of time involved in the manual setting of line stops as heretofore used, and the movement of the 110 line stop incident to the reception of each line by the first elevator is reduced to the lowest possible minimum. As long as the measure for which the machine is set is unchanged, the line stop will move only slightly 115 120 and to an insignificant degree after the delivery of each composed line to the first elevator, and when the measure of the machine is changed, the line stop will accommodate itself to the difference in length with a perfectly free action and without causing any appreciable wear to itself or to the guides in which it travels, the extent of movement of the line stop involved in its resetting for any change in the measure or length of the 130

line being only equal substantially to the difference between the length of the line, as changed, and the length or measure of the line previously used.

5. I claim as my invention:—

1. In a typographical machine having an elevator adapted for the endwise reception of an assembled line, a tensioned line stop associated with such elevator during its 10 movements and positioned to encounter an incoming line, and means to position the line stop according to the length of the incoming line.

2. In a typographical machine having an 15 elevator adapted for the endwise reception of an assembled line, a line stop within such elevator and tending to move in opposition to an incoming line, and means for holding the line stop in set position.

20 3. In a typographical machine of the lino-type class having a first elevator, a line carriage adjustable to receive assembled lines of different measures and operative to deliver such lines to the first elevator, a line stop 25 carried by the first elevator and having a tendency to move against the forward end of an incoming line, and means controlled by the line carriage to position the line stop.

4. In a typographical machine having an 30 elevator, and means for transferring an assembled line endwise thereto, a line stop movable in the elevator and having a tendency to move toward one end of a line therein, and a device for restraining the line stop 35 from movement, said device being releasable by said line transferring means.

5. In a typographical machine of the lino-

type class having a first elevator, and a carriage for delivering an assembled line thereto, a line stop tending to move toward one 40 end of a line in said elevator, a device for restraining the line stop from movement, and means controlled by the line delivery carriage for retracting the restraining device to release the line stop for movement. 45

6. In a typographical machine having an elevator, and a line carriage for delivering an assembled line thereto, a line stop carried by said elevator and tending to move against the end of an incoming line, a device for restraining the line stop, said device being releasable by the line carriage to permit the line stop to adjust itself to the length of the line and reengageable with the line stop to hold it in adjusted position when the elevator commences its descent. 50

7. In a typographical machine of the lino-type class having a first elevator, and a line carriage for delivering an assembled line thereto, a line stop carried by the elevator and having a tendency to move toward an incoming line, a restraining device for the line stop, and means controlled by the line carriage for releasing the line stop from said restraining device when the line carriage approaches the limit of its line transferring movement. 60

In testimony whereof I have hereunto set my hand in presence of two subscribing witnesses.

EDWIN WALTER PIERSON.
